UNITED STATES PATENT OFFICE.

CHARLES B. ASKEW, OF CHICAGO, ILLINOIS.

ELECTRIC SWITCH.

SPECIFICATION forming part of Letters Patent No. 784,022, dated March 7, 1905.

Application filed May 11, 1904. Serial No. 207,349.

To all whom it may concern:-

Be it known that I, CHARLES B. ASKEW, of Chicago, in the county of Cook and State of Illinois, have invented certain new and useful Improvements in Electric Switches; and I hereby declare that the following is a full, clear, and exact description thereof, reference being had to the accompanying drawings, which form part of this specification.

My invention relates to electric switches adapted to automatically open and close one or more electric circuits, and has for one of its salient objects to provide, in a switch of the character described, advantageous means for positively and accurately timing the operation of the switch.

A further object of my invention is to provide such a timing device for a switch of the character described as will be unaffected in operation by changes in atmospheric conditions, by dust, or other adverse conditions of use of the device; and a further object of my invention is to provide a generally-improved, simple, and effective time-switch mechanism of the character indicated.

Other and further objects will also become apparent upon a consideration of the following description and the appended claims.

In the drawings, wherein I have illustrated an operative embodiment of my invention, Figure 1 is a front elevation of a complete double-throw electric time-switch. Fig. 2 is a plan view of the same. Fig. 3 is a central vertical section, and Figs. 4 and 5 are sections taken, respectively, on lines 4 and 5 of Fig. 1.

Throughout the drawings like numerals of reference refer always to like parts.

Referring now to the drawings, 10 indicates a base-plate, preferably of slate or other insulating material, 11 11 indicate feet supporting said plate, and 12 12 indicate two upright bearing-brackets or standards mounted on the plate 10. These parts constitute a convenient frame for the machine, for which, however, any other suitable frame structure might be substituted.

Mounted in bearings in the standards 12 is a rock-shaft 13, having rigidly affixed thereto a lever element extending on both sides

thereof and on opposite sides of the shaft operatively associated with the moving elements of two electromagnetic actuating devices. In the present construction the lever element comprises a wheel 14 peripherally grooved to receive a cable 15 whose opposite ends are connected to the cores 17 and 17' of two solenoids 16 and 16', respectively, said solenoids being preferably suspended below the base-plate 10 of the frame. Associated with the wheel 14 for movement therewith is an oscillating member of the timing device comprising an elongated runway 18, preferably closed throughout and supported on a hub 19, loosely mounted on the shaft 13. In the present instance the runway has a lost-motion connection with the wheel 14 through two pins 20 and 20', projecting from the face of the wheel 14, beneath the casing 18, so that the angular throw of the runway is greater than that of the wheel. It will be apparent, however, that as the oscillating runway is primarily actuated by the solenoids the wheel might be omitted and direct connection made between the runway and the solenoids.

21 indicates a counterbalance-weight mounted on a stem 22, secured to and projecting upward at right angles from the center of the runway 18 for a purpose to be described.

23 indicates a gravity-movable part, preferably a ball, of conducting material, inclosed in the runway-casing 18 and which as the casing is deflected in either direction from a horizontal position rolls to the lower end of the runway and coacts with two relatively stationary electrical contact members to close a circuit therethrough. As best shown in Figs. 4 and 5, the contact members 24 and 25 are preferably arranged in the bottom of the casing and project longitudinally thereof a suitable distance in parallel relation to form, in effect, a track upon which the ball 23 may roll, thereby insuring perfect electrical contact of said ball with both of the contact members. In the electrical connection of the parts the contact members at the left end of the runway are included in normally open circuit with the right solenoid 100

16' and the corresponding contact members at the right end of the runway included in normally open circuit with the left solenoid 16 of the device. Such connections I have 5 diagrammatically illustrated in Fig. 1, where A represents a local battery, from one terminal whereof extends a wire *a*, including in circuit therein the solenoid 16 and terminating in one of the contact members at the 10 right end of the runway 18 and from whose opposite terminal extends a wire *b*, directly connected to the complementary contact-points at the right end of said runway. A like connection is made from said battery by 15 wire *a'*, through the solenoid 16', to a contact-point at the left end of the runway and by wire *b'* direct from the other terminal of the battery to the complementary contact-point at said left end of the runway. It will 20 be apparent now that when the parts are in the position shown in Fig. 1—that is to say, with the left end of the runway depressed—a circuit will be closed by the circuit-closing ball 23 through a path as follows: from battery 25 A through the solenoid 16', by wire *a'* to one of the contact members 24 or 25, through the ball 23 to the other contact member, and back to the battery by the wire *b'*. Consequently the solenoid 16' being energized the 30 core 17' is attracted thereto and the wheel 14 oscillated through a corresponding arc. During this movement the connecting-pin 20 serves to lift the left end of the runway 18 until the latter passes dead-center, or an exactly- 35 horizontal position, when the weight of the counterbalance 21 throws the said runway to the position indicated in dotted lines in Fig. 1—that is to say, with its right end depressed. It will be apparent that as the connection 40 energizing the solenoid 16', established through the ball 23 and the contact members at the left end of the runway will not be broken until after the runway has passed a horizontal position, and 45 as the counterweight 21 will then have moved past its central position and will positively force the runway to complete its throw to dotted-line position the possibility of the runway returning to a full-line position, 50 which it has just left, as soon as the circuit of the solenoid 16' is broken by the ball 23 leaving its contact-points is obviated. Obviously now when the runway is so tilted that its right end is depressed the ball 23 55 rolls to its said right end and there closes the circuit through the solenoid 16, whereupon the operation of the device is reversed and the parts restored to their initial position. (Indicated in full lines in Fig. 1 of the drawings.) It will be apparent that the frequency 60 of operation will depend upon the length of time consumed by the relatively movable circuit-closing member 23 in its traverse of the runway, and this time movement may 65 be controlled in various ways. I have

herein shown and prefer to employ as a means for regulating the speed of the ball a series of impediments in the path of the ball. To this end I prefer to successively deflect portions of the runway in opposite directions to make a tortuous passage in the traverse of which the direction of motion of the ball must be a number of times reversed and its progress thereby temporarily checked. It will be apparent, however, that other 75 forms of impediments for checking the ball's traverse might be introduced into the runway or that the entire casing might be filled with a liquid which would serve as such impediment to the traverse of the ball. Should 80 the liquid be used, the time movement in the operation of the device might be readily varied by varying the viscosity of the liquid.

Associated with the parts described are provided switch or circuit-closing elements 85 for the main circuit, arranged to be actuated by the solenoids 16 and 16'. In the present illustrative embodiment the switch employed is a double-throw snap-switch, the construction whereof I will now describe. 90

26 indicates a switch-arm loosely mounted on the shaft 13 and extending on both sides thereof.

27 27 indicate knife switch-blades mounted on or formed integrally with the switch-arm 95 26 and adapted to coact with the stationary switch members 28 and 28', mounted on suitable brackets 29 29', secured to the base-plate 10.

A three-wire circuit may be connected to 100 the switch by connecting the common wire of the two branches of the circuit to a binding-post 26^a, mounted on one of the standards 12 and connecting the other two wires, respectively, to the binding-posts 29^a and 29^b 105 of the brackets 29 and 29'.

The movable switch-arm 26 is provided with a vertically-projecting finger 30, provided with a forwardly-projecting pin 31, and the latter is connected by a compression-spring 32 with the pin 33, carried by a depending finger 34, rigidly keyed or otherwise secured to the shaft 13. The finger 34 is so positioned that during the oscillation of the shaft 13 due to the operation of the opposing 110 solenoids it swings through equal arcs upon opposite sides of a vertical line, while the movement of the switch-arm 26 is so limited by suitable stop-pins 35 and 35', carried for convenience by the standards 29 and 29', 115 that the angular movement of the finger 30 of the switch-arm on either side of a vertical line is less than the angular movement of the said finger 34, carried by the shaft. It will be apparent, therefore, that when the parts are 120 moved in the position shown in full lines in Fig. 1 to the position indicated in dotted lines in Fig. 1, under the influence of the solenoid 16', the pin 33, to which the lower end 125 of the spring 32 is connected, is moved to the 130

position shown in dotted lines, thereby carrying the tension-line of the spring over to the right side of the line of centers of the switch-arm finger 30 and the shaft 13. The 5 switch-arm 26 will accordingly be snapped sharply from its position of engagement with the right-hand stationary switch member 28' to position of engagement with the left stationary switch member 28, such movement 10 taking place before the ball has completed its traverse to reverse the solenoid connections. The subsequent reversal of the solenoid connections by the timed circuit-closer, causing a restoration of the runway 15 to full-line position, will of course be followed by a concomitant, but opposite, reversal of the switch-arm 26, and the alternations thereafter continue indefinitely at regular intervals.

20 It will be apparent that as the movable timing element is completely inclosed and gravity-impelled there is nothing about the timing mechanism to get out of order from exposure to the weather and that wear will 25 have little or no effect on its operation.

While I have herein described with some particularity one specific form of snap-switch which I prefer to employ to obtain quick action on both make and break of the main circuit, I do not desire to be understood as limiting the use of the timing device to this particular switch, as it will be apparent that certain features of my invention herein described might be used in conjunction with 35 any form of switch mechanically susceptible of connection for operation with the timing element. It will further be apparent to those skilled in the art that numerous variations in the mechanical embodiment of my invention 40 might be made without departing from the spirit and scope thereof.

Having thus described my invention, what I claim, and desire to secure by Letters Patent of the United States, is—

45 1. In an automatic switch, an oscillating switch-arm, means for oscillating said arm including electromagnetic devices arranged to move the arm in opposite directions, circuits for the electromagnetic devices, and a timing switch device for said circuit operatively associated with the electromagnetic devices for actuation thereby, said timing switch device being arranged to effect the circuit of one of the electromagnetic devices to 50 energize the same when actuated by the other electromagnetic device and timed to operate subsequently to the operation of the oscillating switch-arm.

2. In an automatic switch, an oscillating 55 switch-arm, means for oscillating said arm including two solenoids arranged to move the arm in opposite directions, normally open circuits including said solenoids, and a timing circuit-closer for said circuits arranged to 60 alternately close the circuit through the so-

lenoids subsequently to the operation of the oscillating switch-arm.

3. In an automatic switch, an oscillating switch-arm, means for oscillating said arm including solenoids arranged to move the 70 arm in opposite directions, normally open circuits including said solenoids, and means for closing the circuit through either solenoid at a predetermined interval after the closing of the switch under the influence of the other 75 solenoid.

4. In an automatic switch, an oscillating switch-arm, means for oscillating said arm including two solenoids arranged to move the arm in opposite directions, normally open 80 circuits including said solenoids, and a gravity circuit-closer arranged to close the circuit through each solenoid at a predetermined time after the movement of the switch-arm under the influence of the opposite 85 solenoid.

5. A timing device for automatic switches, comprising an oscillating member, an electromagnetic device for moving said member in one direction, means for moving said 90 member in the opposite direction, circuit-closing devices carried by said oscillating member, including relatively stationary contact parts, and a contact part movable in accordance with the movement of the oscillating 95 member into or out of position of co-operation with the relatively stationary parts, a source of electrical supply, and circuit connections including said source of supply, the electromagnet and the relatively stationary 100 contact parts.

6. A timing device for automatic switches, comprising an oscillating member, two electromagnetic devices for moving said member in opposite directions, circuit-closing devices 105 carried by the oscillating member including relatively stationary contact parts, and a contact part movable in accordance with the movement of the oscillating member to contact-closing position with reference to either 110 of the relatively stationary contact parts, and circuit connections from the electromagnets each to one of the opposing relatively stationary contact parts.

7. In a timing device for automatic 115 switches, comprising an oscillating runway, electromagnetic instrumentalities for oscillating said runway, circuit-closing means carried by said runway including relatively stationary parts near each end of the runway, 120 and a part movable toward and from said relatively stationary parts consistently with the oscillating runway, to close or open circuit through the corresponding stationary parts, a source of electrical supply and circuit 125 connections including said source of supply, the electromagnetic instrumentalities, and the relatively stationary contact parts.

8. In a timing device for electric switches, 130 an oscillating runway, two electromagnetic

instrumentalities for moving said device in opposite directions, contact parts adjacent each end of said runway, each arranged in normally open circuit with the electromagnet instrumental in elevating said end of the runway and a gravity circuit-closing instrumentality arranged in said runway for coaction with either of the relatively stationary contact parts.

10 9. In a timing device for electric switches, a tortuous runway mounted for oscillation to position of inclination in opposite directions, contact members carried by said runway adjacent each end thereof, the contact mem-

bers adjacent each end of the runway being 15 arranged in circuit with the electromagnetic device instrumental in elevating the said end of the runway, and a circuit-closing instrumentality consisting of a ball mounted to roll in said runway.

20

In testimony that I claim the foregoing as my own I affix my signature in presence of two witnesses.

CHARLES B. ASKEW.
